Primary Examiner — Lakiya G Rogers*Assistant Examiner* — Michelle K. Lu(74) *Attorney, Agent, or Firm* — YK Law LLP; Michael A DiNardo(57) **CLAIM**

The ornamental design for a light fixture, as shown.

DESCRIPTION

FIG. 1 is a perspective view from an elevated angle of the light fixture of the present invention;

FIG. 2 is a perspective view from a lowered angle of the light fixture of the present invention;

FIG. 3 is a front view of the light fixture of the present invention;

FIG. 4 is a back view of the light fixture of the present invention;

FIG. 5 is a right side view of the light fixture of the present invention (the left-side view is a mirror image);

FIG. 6 is a top view of the light fixture of the present invention;

FIG. 7 is a bottom view of the light fixture of the present invention; and,

FIG. 8 is an environmental view of FIG. 1.

The broken lines in the drawings illustrate features of the light fixture that form no part of the claimed design.

1 Claim, 7 Drawing Sheets(56)
